UNITED STATES PATENT OFFICE

FRANK P. READ, OF ST. PETERSBURG, FLORIDA

DESIGN FOR A ROTARY GAME DEVICE

Application filed November 26, 1930. Serial No. 37,789. Term of patent 3½ years.

To all whom it may concern:

Be it known that FRANK P. READ, a citizen of the United States of America, residing at St. Petersburg, in the county of Pinellas and State of Florida, has invented a new, original, and ornamental Design for Rotary Game Device, of which the following is a specification, reference being had to the accompanying drawings, forming part thereof.

Figure 1 is a plan view of a rotary game device, showing my new design.

Figure 2 is a cross section on line 2—2 of Figure 1.

I claim:

The ornamental design for a rotary game device, as shown.

In testimony whereof I affix my signature.

FRANK P. READ.
